US0D1061257S

(12) **United States Design Patent** (10) **Patent No.:** **US D1,061,257 S**
(45) **Date of Patent:** **** Feb. 11, 2025**

(54) **PACKAGE FOR FLUIDS**

(71) Applicant: **SIG Combibloc (Suzhou) Co., Ltd.**
Suzhou (CN)

(72) Inventors: **Remo Zürcher**, Jiangsu (CN);
Qingyang Liang, Jiangsu (CN)

(73) Assignee: **SIG Combibloc (Suzhou) Co., Ltd.**
Suzhou (CN)

(**) Term: **15 Years**

(21) Appl. No.: **35/519,791**

(22) Filed: **Jan. 20, 2023**

(80) **Hague Agreement Data**

Int. Filing Date: **Jan. 20, 2023**

Int. Reg. No.: **DM/227450**

Int. Reg. Date: **Jan. 20, 2023**

Int. Reg. Pub. Date: **Jan. 26, 2024**

(30) **Foreign Application Priority Data**

Jul. 26, 2022 (CN) 202230479647.2

(51) **LOC (15) Cl.** **09-01**

(52) **U.S. Cl.**

USPC **D9/560; D9/432**

(58) **Field of Classification Search**

USPC D9/516, 519, 529, 549, 562, 572, 573,
D9/574, 575, 530, 531, 532, 535, 536,
